UNITED STATES PATENT OFFICE.

LEON FEIGELMAN, OF NEW YORK, N. Y.

BINDER AND LINING HOLDER.

1,317,566.

Specification of Letters Patent. Patented Sept. 30, 1919.

Application filed April 16, 1919. Serial No. 290,428.

To all whom it may concern:

Be it known that I, LEON FEIGELMAN, a citizen of Russia, and a resident of the city of New York, borough of the Bronx, in the 5 county of the Bronx and State of New York, have invented a new and Improved Binder and Lining Holder, of which the following is a full, clear, and exact description.

This invention relates to attachments for 10 sewing machines and particularly to an improved binder and lining holder which will guide the binding and lining simultaneously so that a single line of stitching will connect all these parts together.

15 Another object in view is to provide an apparatus for causing the sewing machine to sew together simultaneously the lining, a binding and a reinforcing member.

A further object of the invention is to 20 provide a guide for guiding a binder over a reinforcing and at the same time guiding a piece of lining so as to be stitched in place by the same line of stitching that connects the binding with the reinforcement.

25 Another object, more specifically, is the arrangement of means for guiding a lining which may be adjusted independently of the stitching mechanism and the article to which the lining is secured.

30 In the accompanying drawing:

Figure 1 is a perspective view showing an embodiment of the invention positioned ready for use.

Fig. 2 is a side elevation of the holder 35 shown in Fig. 1.

Fig. 3 is a fragmentary sectional view through Fig. 1 approximately on line 3—3.

Fig. 4 is a top plan view of the holder 40 shown in Fig. 1 adjusted to a different position.

Fig. 5 is a sectional view through a lining strip after it has been completed.

In providing lining in trousers or other garments it is necessary to provide a lining 45 member 1 which may extend any desired distance. To this lining member 1 is attached a reinforcing or stiffening band 2 having a binding 3 secured thereto. In the present invention an improved binder and lining

50 holder has been provided which will provide a single line of stitching 4 as shown in Fig. 5 which will connect the stiffening member 2 and the binding 3 and at the same time will connect the lining 1 to the binding 3.

55 When the parts are guided past the needle the same are straight and the parts are al-

ways held in proper position so that the finished article will be substantially perfect.

The holder for accomplishing this result is disclosed in Figs. 1 to 4 and preferably 60

consists of two members, namely a stiffening and binding holder 5 and a lining holder and guide 6.

The particular shape in cross-section of holder 5 is shown in Fig. 3, said shape being substantially V-shaped with the 65

ends bent inward for holding the binding 3 in place while the reinforcing 2 is projected to the bent line of the binding. The holder 6 holds the lining 1 in place whereby the

needle of the sewing machine may freely 70 pass through all of these members simultaneously. The lining guide 6 is substan-

tially U-shape in cross-section as shown in Fig. 3 and is arranged above the guide and holder 5, the rear end being comparatively 75

wide open while the front end is almost closed in a similar manner to the shape of the guide 5. The guide 5 is preferably con-

nected with a base 7 which may be of any desired kind, as for instance an ordinary flat 80

plate with one or more openings 8 for re-

ceiving retaining screws. The plate 7 may be of any size and any shape so as to allow the device to be applied to the different

makes of sewing machines now in common 85

use, or others that may be produced. The holder 6 is connected with a supporting base

member 9 having one or more apertures 10 for receiving screws 11 whereby member 6

may be adjusted back and forth with respect 90

to the member 5, in order that the lining 1 may be stitched to the binding 3 and rein-

forcing 2 as shown in Fig. 5, or close to the edge or farther from the edge as desired. With the parts adjusted as shown in Fig. 4 95

the line of stitching would be nearer the upper edge of the binding than when posi-

tioned as shown in Fig. 5. The back and forth adjustment of member 6 determines

the position of the lining 1 in respect to 100

binding 3, while the back and forth move-

ment of the member 5 and its supporting

base or plate 7 determines the position of

the line of stitching 4 in respect to the lin-

ing 1.

What I claim is:

1. An attachment of the character de- 110

scribed, comprising two members, one of

said members being substantially V-shape

in cross section and having inwardly pro-

jecting edges for overlapping the edges of

a binding strip and causing the same to

fold as it is moved longitudinally, said member also guiding a reinforcing with its edge in the fold of the binding, the second of said members being a guide member having adjustable connection with the first-mentioned member and adapted to guide a lining.

2. An attachment of the character described, comprising two members, one of said members of substantially V-shape in cross section having inwardly projecting edges for overlapping the edges of a binding strip and causing the same to fold as it is moved longitudinally, the said member also

guiding a reinforcing with its edge in the fold of a binding strip, the second of said members being a guide member adapted to guide a lining into position to be sewed to the binding strip and the reinforcing by single line stitch, a base for each member, and means connecting said bases and permitting lateral adjustment of one member relative to the other, and one of said members constructed to permit lateral adjustment of the attachment on the sewing machine to which it is adapted to connect.

LEON FEIGELMAN.
